ROBERT H. BEAUMONT, OF RADNOR, PENNSYLVANIA, ASSIGNOR TO R. H. BEAUMONT CO., OF PHILADELPHIA, PENNSYLVANIA, A CORPORATION OF PENNSYLVANIA.

MATERIAL STORAGE AND HANDLING SYSTEM.

Application filed April 22, 1925. Serial No. 25,012.

This invention relates to systems for storing and subsequently handling coal, gravel, sand and other granular or pulverulent materials—more particularly systems wherein bunkers of the suspension type are employed as the storage hoppers. Such bunkers, by reason of being constructed of flexible sheet metal and supported wholly in suspension, yield to distortion—both vertically and laterally—directly in proportion to variations in contents or load. As a consequence, the bottom discharge-directing outlets (which in accordance with customary practice heretofore were bolted directly to the bunker shells) would be correspondingly shifted and their closure gates disaligned relative to the mechanism provided for actuating them.

My present invention is concerned with overcoming the difficulty above pointed out, and directed to improvements to that end.

The drawing herewith shows a cross sectional view of a material storage and handling system for a power plant conveniently illustrating my invention.

The coal storage bunker herein comprehensively designated 1, has its sheet metal shell hung in suspension from the top of a frame work 2 comprising spaced verticals 3 as well as horizontals 4, all of structural shapes appropriately braced after standard engineering practice.

Beneath the bunker 1 is shown a larry 5 capable of receiving the material in its hopper 6 and transferring the same, through selection as between the delivery chutes 7, 7, to the stokers 8 of boilers aligned along opposite sides of the frame structure 2. The wheels 9 of the larry 5 run on rails 10 which extend longitudinally of the bunker 1 and are supported by suitable struts 11 dropped from the cross beams 4. In addition to the usual driving means and controlling gear, which need not be specifically referred to herein, the larry 5 is equipped with mechanism for operating the pivoted controlling gate 12 of the outlet 13 through which the bunker 1 is discharged.

The gate operating mechanism, just referred to, includes a hand wheel 14 that is convenient of access to the operator's seat 15 in the larry 5, the movements of said hand wheel being transmitted by a sprocket chain or cable 16 to an overhead rock shaft 17. On this shaft 17 is secured a hooked

finger 18 adapted to engage and draw upon the projecting actuating link 19 of the control gate 12 to shift the latter to open position in a manner obvious from the illustration.

For reliable operation of the gate 12 the link 19 should, obviously, always be in position for ready cooperation with the hooked finger 18 of the operating mechanism on the larry 5; but with the control gate and discharge outlet directly secured to the bunker shell as heretofore, the actuating link was often so much displaced through distortion of the bunker under varying or unevenly distributed loads, as to be quite out of reach of the hooked finger aforesaid. This contingency I prevent in accordance with my invention, by independently supporting the discharge outlet 13 and gate 12 rigidly so that the alignment between the link 19 and the operating finger 18 is always positively and accurately maintained. Accordingly, I secure in spaced parallel relation between certain of the transverse beams 4 of the frame structure 2, a pair of channel pieces 20, and affix the outlet 13 to said channel pieces thereby forming a sort of pocket 21 which, as shown, is amply proportioned to receive the outflow through the flanged opening 22 in the bottom of the bunker 1 notwithstanding positional changes due to the influences previously noted.

Having thus described my invention, I claim:

1. In material handling systems, the combination of a suspension bunker with an outlet, and a separate auxiliary outlet for directing gravity discharge from the bunker, said outlet being independently supported for security against positional displacement incidental to distortions of the bunker under varying or unevenly-distributed loads.

2. In material handling systems, the combination of a suspension bunker with an outlet, and a closure gate with mechanism to operate it in controlling discharge from the bunker, said closure gate being independently supported by an auxiliary outlet for security against displacement relative to its operating mechanism incidental to distortions of the bunker under varying or unevenly-distributed loads.

3. In material handling systems, the combination of a suspension bunker with an

outlet, an independently-supported auxiliary outlet, a larry shiftable beneath the bunker, a closure gate for controlling discharge from the bunker through the auxiliary outlet into the larry, said gate being supported by the auxiliary outlet, and mechanism on the larry for operating said

gate with security against disalignment incidental to distortions of the hopper under varying or unevenly-distributed loads.

In testimony whereof, I have hereunto signed my name at Philadelphia, Pennsylvania, this 15th day of April, 1925.

ROBERT H. BEAUMONT.
